UNITED STATES PATENT OFFICE

EDWIN J. DOWNING, OF DENVER, COLORADO, ASSIGNOR TO GARDNER-DENVER COMPANY, OF DENVER, COLORADO, A CORPORATION OF DELAWARE

SCREEN

Application filed May 3, 1928. Serial No. 274,831.

The present invention relates to screens particularly intended for removing particles of dirt from air used to operate pneumatic tools or the like.

5 The object is to provide a simple, compact structure that can be placed in the hose line and will occupy but little space, said means constituting an effective screen and one which can be easily cleansed.

10 In the accompanying drawings:

Figure 1 is a view in side elevation of the preferred form of structure.

Figure 2 is a longitudinal sectional view showing the same in place in an air line.

15 Figure 3 is a cross sectional view taken on the line 3—3 of Figure 2.

In the embodiment disclosed a substantially cylindrical casing 4 is employed having a relatively large internal chamber 5 and reduced terminal portions 6 and 7, one, as 6, being provided with an inlet port 8 and the other with an outlet port 9. The terminal portion 6 is provided with opposite longitudinal external ribs 10 preferably formed 20 in the shape of arrows, to indicate that said terminal is the inlet end. The walls of the inlet and outlet ports are internally threaded to receive the sections 11 and 12 of a conduit. The section 12 is shown in the form of the 25 usual goose-neck that is attached to the drilling motor of a rock drill.

30 Located within the chamber 5 and adjacent to the outlet port 9 is a cup 13 whose open end faces the inlet port 8 and has an internal diameter substantially the same as the said inlet port. The bottom of this cup is conical. The side walls of this cup 13 are spaced from the chamber walls except for the provision of webs 14 that serve as supports for the 35 said cup. Obviously therefore, as shown in Figure 2, there is free communication between the inlet port and the outlet port through the chamber and around the cup 13.

40 A cylindrical open ended screen 15 has its ends fitted into the inner end of the inlet port 8 and the interior of the cup 13. This screen is preferably made of a sheet of resilient metal that can be bent around the finger and placed in position, its expansive 45 action thus assuring its ends having tight

fits or bearings in the inlet port and cup. To prevent the outward longitudinal displacement of the screen, a split ring 16 is fitted into the inner end of the inlet port and the walls thereof at said inner end are provided with a seat 17 to receive the ring 16. This ring thus constitutes an abutment for the outer end of the screen and because of the conical interior formation of the cup and the expansible properties of the screen, said 55 screen will be forced snugly against the ring. 60

As clearly indicated in Figure 2, air flowing through the conduit must pass into the interior of the screen, thence outwardly therethrough into the chamber, and on to the outlet 65 around the cup. The screen can be readily removed and it may be cleaned by reversing the flow of air through the casing.

70 From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the 75 advantages of the invention.

What I claim is:

80 A screen for air lines and the like comprising a casing having a passageway therethrough and means for coupling conduit sections to its ends, a cup within the passageway having a tapered bottom, an expansible tubular screen having one end that engages 85 the tapered bottom, said screen by its expansive action on the tapered bottom being urged longitudinally, and a removable abutment ring in one end of the casing and against which the other end of the screen engages 90 when so urged longitudinally.

95 In testimony whereof, I affix my signature.

EDWIN J. DOWNING.
